COMBINED SPEAKER AND DISPLAY CABINET FOR JEWELRY OR THE LIKE

Henry A. Schwartz, Valley Stream, N.Y., assignor, by
mesne assignments, to D. & D. Special Tools, Inc., a
corporation of New York

Filed Dec. 3, 1962, Ser. No. 72,680

Term of patent 3½ years

(Cl. D80—11)

FIG. 1

FIG. 2

FIG. 3

FIG. 1 is a front elevational view of a combined speaker and display cabinet for jewelry or the like embodying my new design, the rear being solid and plain.

FIG. 2 is a side elevation view thereof.

FIG. 3 is a top plan view thereof.

It is to be understood that the fragmentary cross hatching on the small rectangular front panels (FIG. 1) representing fabric is continuous throughout said panels.

I claim:

The original design for a combined speaker and display cabinet for jewelry or the like, as shown and described.
